SANDING DEVICE

Charles Earl Rosemeyer, Seattle, Wash.

Application May 16, 1947, Serial No. 748,509

1 Claim. (Cl. 51—187)

1

My invention relates to hand sanding devices. The principal object of my invention is to provide a sander which is economical in manufacture and easily and effectively handled in smoothing and finishing surfaces.

Another object of the invention is to provide a sanding device in which the sand paper or the like may be readily affixed and removed from the tool.

A further object of my invention is to provide a sander which will permit the full utilization of the sanding or abrasive surface and at the same time provide a longer life to said abrasive surface. Referring now more specifically to the accompanying drawings which illustrate my invention:

Fig. 1 is a perspective view of my sand paper block with the sand paper gripped ready for use.

Fig. 2 is a perspective showing the cover turned spreading the clamps in releasing the sand paper.

Fig. 3 is a perspective of the body of the sand paper block.

Fig. 4 is a plan view of the block with the top cover removed.

Referring more particularly to the drawings, reference numeral 6 (Fig. 3) represents the body of the block in its entirety. The top surface 7 of the block is provided with two elevated longitudinal ribs 8 and elevated portions 9 between which and the ribs 8 are formed grooves or slides 10. Below the surface 7 is an elliptical depression 11, below the bottom surface of which is a round depression 12, the centers of the depressed ellipse 11 and depressed circle 12 coinciding with the center of the block 6. In the center of the block (also the center of the depressed ellipse 11 and circle 12) is firmly secured an upright bolt 13 threaded at its top end as shown at 14. The ends of the block 6 are notched out as shown at 15 into which is cemented soft rubber blocks 16 the top edge of which is flush with the surface 7 of the block. The thickness of the rubber blocks 16 is slightly less than the width of the notches 15 thus forming a narrow shoulder 17. The top edges of the block 6 are grooved out as shown at 18 to form convenient hand grips. The lower surface of the block 6 is provided with a rubber pad 19 the exact size of the surface.

Referring to Figures 2 and 4 reference numeral 20 represents two metal plates bent down at their outer ends as shown at 21. The edges of the plate are cut away as shown at 22 and the inner ends are cut away as shown at 23 forming two narrow legs 24 which are free to slide in grooves 10 in the top of the block.

2

Reference numeral 25 represents two curved levers consisting of a straight portion 26 and inner curved ends 27. In the ends of the straight portion 26 are rigidly secured small upwardly projecting pins 28 the upper end of which pass freely through holes 29 in the metal plates 20. The inner curved portion 27 of the levers are perforated to rotatively receive upwardly projecting screws 30 the upper end of which are screwed into the under side of the top cover 31. The top cover is drilled in the center so as to rotate freely about the center bolt 13. The center of the cover 31 is counter sunk as shown at 32 (Fig. 2) to receive the nut 33 threaded over the top of the bolt 13.

Reference numeral 34 represents a strip of sand paper with upturned ends 35. When the top cover 31 is in registry with block 6 as shown in Fig. 1 the metal plates 20 are drawn inwardly towards each other as shown in Figs. 1 and 4. Their downwardly bent ends 21 gripping the upwardly turned ends 35 of the sand paper. The resiliency of the rubber block 16 as will be noted form a more positive grip on the upturned ends 35 when the downturned ends 21 of the metal plates 20 are clamped against it.

The method of operation is as follows:

To place a sand paper in the block the cover 31 is first turned in the direction of the arrow 30 (Fig. 2) until it is crosswise of the body 6 as shown. The rotation of the cover 31 it will be noted (Fig. 4) rotates the screws 30 about the bolt 13 moving the ends of the levers 25 with them till they occupy the position shown in the dotted lines (Fig. 4), the upwardly projecting pins 28 of the levers 26 moving the metal plates 20 outwardly away from each other till they occupy the position shown in the dotted lines in Fig. 4 and also in the position shown in Fig. 2. The strip of sand paper 34 now is cut to the proper length and the ends turned upwardly as shown (Fig. 2). The ends 35 of the sand paper are now slipped upwardly between the rubber blocks 16 and the downwardly turned ends 21 of the plates 20 and the cover 31 turned back to the position as shown in Fig. 1 the ends 21 of the metal plates firmly gripping the ends of the sand paper against the rubber block 16 and the sand paper block is ready for use.

Having described my invention I claim:

In a holder of the character described, a pair of members in movable superposed relation, one of said members having its inner face provided with a pair of recesses, one of which being below and within the other, raised portions on said

member on either side of said larger, upper recess, a pair of levers within said recess, screws upon which said levers are rotatably mounted, upwardly projecting pins disposed at the outer ends of said levers, means for moving said levers in opposite directions, metal plates at either end of said lower member and movably positioned thereon, cushions provided at either end of said lower member, a bottom plate with its sides bent

5 at right angles and adapted to fit snugly over said lower plate, an abrasive sheet to fit over said bottom plate and bent in conformity therewith so as to engage the said metal and plates when same are opened by the action of said levers in their outward thrust and closed by the turning of the upper member in their inward thrust.

CHARLES EARL ROSEMEYER.
